UNITED STATES PATENT OFFICE.

HERMANN STELZNER, OF LÜBECK, GERMANY, ASSIGNOR TO THE FIRM OF DRÄGER-WERK, HEINR. & BERNH. DRÄGER, OF LÜBECK, GERMANY.

DIVER'S HELMET.

1,159,125.

Specification of Letters Patent.

Patented Nov. 2, 1915.

Application filed August 22, 1912. Serial No. 716,476.

To all whom it may concern:

Be it known that I, HERMANN STELZNER, a subject of the Emperor of Germany, residing at 3 Uhlandstrasse, Lübeck, in the 5 German Empire, have invented certain new and useful Improvements in Divers' Helmets, of which the following is a specification.

The helmets hitherto employed for diving 10 apparatus are formed of a rigid material such as metal. The helmet is so far as I am aware fixed as a separately closing part on the air-tight dress of the apparatus in such a manner that the interior of the costume 15 is spatially connected with the helmet. This arrangement has given rise to accidents, the cause of which has hitherto been inexplicable. If the diver is working at a depth of 5 meters under water, the pressure 20 prevailing around him is one and a half atmospheres, and this applies equally to the interior of the helmet and the dress. Now if it should happen that the diver suddenly sinks considerably deeper, for example if 25 when working on a ladder he should fall therefrom or if when walking on the sea bottom he should fall into a depression, the pressure is proportionately increased. For example, if he has fallen from a depth of 30 5 meters to a depth of 10 meters, the pressure surrounding him increases from $1\frac{1}{2}$ atmospheres to 2 atmospheres and correspondingly the air contained in the dress and in the helmet will be compressed to the 35 extent of one quarter its previous volume. If the dress is exhausted of air, as only the air contained in the helmet is present, the body is forced into the helmet and the trunk pressed vigorously against the lower 40 edge of the helmet without the pressure prevailing in the helmet being considerably increased. The result of this is that the blood in the body exposed to the increased pressure is forced toward the head; in the case of 45 small differences of pressure fainting fits and other difficulties or injuries will be occasioned while death may result from greater differences of pressure. Even when air is contained in the diving dress, the same result 50 may arise if equalization of pressure between the dress and the helmet is prevented or impeded owing to the fact that the clothing of the diver, his neck cloth or the like constitutes a packing for the helmet to a 55 greater or less extent. Consequently, al-

though when the diving dress is filled with air accidents of the kind indicated occur less frequently, still they are not impossible, especially when the alteration in the pressure arises very suddenly. Compensation between the pressure of the air in the dress and in the helmet does not take place immediately even when the inlet to the helmet is not completely closed and frequently a very short period of time is sufficient to cause the 60 death of a man in the case of congestion of the blood.

In accordance with the present invention these defects are avoided owing to the fact that the helmet is made of pliable or resilient 70 material, such as rubber, fabric or the like. Preferably the helmet is formed from the same material as the dress. The increased pressure arising in the case of a fall in this case also produces a compression of the 75 inclosed air to the extent of a quarter in the example selected. The pressure does not, however, act only upon the trunk and limbs but also upon the head, so that the blood cannot rise to the head, but equilibrium is 80 produced throughout the entire body so that the diver is able to adapt his quantity of air to the fresh depth uninfluenced by bodily impediments.

In the accompanying drawing Figure 1 85 illustrates a man clad in a diving dress, the latter in section, and Fig. 2 illustrates the perforated casing inclosing helmet.

The helmet *a* is prepared from a pliable or resilient material like the dress *b* to which 90 it is fixed over the shoulders, with which object the two parts may comprise stiff edges *c* and *d*. The sleeves *e* can be closed over the wrists in the known manner and provided with resilient packing rolls or beadings *f* in order to insure perfect freedom of 95 movement for the hands at work. If desired, however, gloves can be provided.

When the helmet is made of elastic material, it may advantageously be provided with 100 a special insertion or covering of considerable tensile strength in order that it may afford a certain resistance to excessive internal pressures. On leaving the water the quantity of air contained in the dress expands 105 and if the diver should leave the water too suddenly or if a sufficient quantity of air is not discharged at once, very considerable differences of tension arise.

If desired the pliable or elastic helmet 110

can be surrounded by a stiff but perforated helmet *g* or a rigid sieve like casket or the like in order to protect the head of the wearer from external influences, blows and so forth.

What I claim and desire to secure by Letters Patent of the United States is:—

A diver's helmet constructed of flexible water-proof material of considerable tensile

strength and a perforated casing inclosing ¹⁰ the said helmet and formed of rigid material.

In testimony whereof I affix my signature in presence of two witnesses.

HERMANN STELZNER.
